UNITED STATES PATENT OFFICE.

HENRY W. BANTA, OF NEWARK, NEW JERSEY, ASSIGNOR TO WESTERN ELECTRIC COMPANY, INCORPORATED, OF NEW YORK, N. Y., A CORPORATION OF NEW YORK.

SEALING LEADING-IN CONDUCTOR.

Application filed November 19, 1923. Serial No. 675,486.

To all whom it may concern:

Be it known that I, HENRY W. BANTA, a citizen of the United States of America, residing at Newark, in the county of Essex

and State of New Jersey, have invented certain new and useful Improvements in Sealing Leading-In Conductors, of which the following is a full, clear, concise, and exact description.

10 This invention relates to evacuated glass vessels for electrical use and particularly to leading-in conductors for such apparatus.

An object of the invention is to provide a leading-in conductor of a form which may 15 be easily applied to the vessel to form an enduring air-tight seal having a minimum liability to be destroyed by mechanical strains or by strains due to the differences in the expansion or contraction of the two 20 materials forming the joint.

In accordance with one feature of this invention, the conductor used is of tubular perforate form, adapted to be securely embedded in the vessel by the glass thereof.

25 Another feature of this invention relates to the method of forming the seal which consists in general of inserting a slug or lump of the glass into the tubular perforate conductor and fusing the glass upon the outside 30 and inside of the conductor to completely embed the same.

The drawings show one embodiment of the invention.

Fig. 1 shows partly in section the braided 35 wire with the slug inserted.

Fig. 2 illustrates the method of forming the seal.

Fig. 3 shows the completed seal.

Fig. 4 shows a pair of conductors sealed 40 into a vacuum tube.

A hollow braided wire 5, preferably of the variety known as "rat-tail," and formed of a metallic substance having a melting point higher than that of glass, is sealed by heat 45 over a slug of glass 6. The whole is then placed within a hollow glass tube 7, against which is directed a flame 8 which softens

the tube so that it will fit closely about the wire-covered slug. Upon the application of further heat, the slug and the tube are 50 melted together about the braiding of the wire, forming an airtight seal for the conductor. After the seal is formed, and, preferably, while the tube 7 is still hot, one end thereof may be cut away as shown in 55 Fig. 3.

The invention is peculiarly adapted for use in sealing leading-in conductors in vacuum tubes and the like, as shown in Fig. 4, in which a conductor is used having a higher 60 coefficient of expansion than the glass of the tube. In the usual form of such tubes, the conductor is formed in a single heavy strand which, because of its higher coefficient of expansion, presses, when heated, against the 65 glass of the seal, tending to crack the glass and destroy the seal. Moreover, by making slight bends 9 in the plated conductor within the tube, all tendency of the wire to press against the seal can be completely avoided, 70 as the expansion of the wire will then only cause an increase in the sharpness of the bends 9 which the flexibility of the wire readily permits.

What is claimed is:

1. The method of sealing a tubular perforate member into a wall of ceramic material which consists in placing some of the material inside the member, surrounding the outside of the member with ceramic material, 80 and fusing together the ceramic material inside and outside the member.

2. The method of forming seals for leading-in conductors in glass vessels for electrical use which consists in forming a tubular, 85 perforate conductor, placing a piece of glass within the tubular member, surrounding the tubular member with glass and fusing together the glass upon the outside and the inside of the tubular member.

In witness whereof, I hereunto subscribe my name this 12th day of November, A. D. 90 1923.

HENRY W. BANTA.
